UNITED STATES PATENT OFFICE.

PHILIPPE AUGUSTE ROCHON AND ANTOINE LAURENDEAU, OF MONTREAL, QUEBEC,
CANADA, ASSIGNORS OF ONE-THIRD TO WILLIAM ROCHON, OF MONTREAL, CANADA.

FURNACE.

1,165,450.

Specification of Letters Patent. Patented Dec. 28, 1915.

Application filed May 22, 1915. Serial No. 29,872.

To all whom it may concern:

Be it known that we, PHILIPPE AUGUSTE ROCHON and ANTOINE LAURENDEAU, both subjects of the King of Great Britain, residing at No. 439 Dufresne street and No. 11 Fullum Lane, respectively, in the city of Montreal, Province of Quebec, Canada, have invented certain new and useful Improvements in Furnaces; and we do hereby declare that the following is a full, clear, and exact description of the invention, such as will enable others skilled in the art to which it appertains to make and use the same.

The invention to be hereinafter described relates to furnaces.

In order to more clearly disclose the construction, operation, and use of the invention, reference should be had to the accompanying drawings forming part of the present application.

Throughout the several figures of the drawings like reference characters designate the same parts.

In the drawings: Figure 1 is a fragmentary side view of the furnace broken away to show the interior construction; Fig. 2 is a section on line 2—2 of Fig. 1 looking down; and Fig. 3 is a front end view of the furnace broken away to show the interior construction.

The main objects of the invention are to provide a compact, efficient, and durable furnace specially adapted to be heated by gas generated from the coal which would ordinarily be used in the fire bed.

Referring to the drawings in detail, the tubular boiler 1 of usual construction is mounted in the usual concrete or brick housing or casing 2 supported by a concrete base 3. At the front of the casing 2 the base 3 is slightly raised and a brick block 4 is erected thereon. An arch 5 is provided in the central portion of this block and extends from the front to the back thereof. On the inner face of this arch the bricks are arranged alternately on their sides and ends, those on their ends being arranged in staggered order. This provides a number of radially disposed tortuous air passages on the inner surface of the arch, for a purpose to be later disclosed. The outer end of the arch communicates with several openings 6 through the front wall of casing 2. The end of the boiler above block 4 is, of course,

bricked in in the usual manner to shut off 55 direct communication of the arch to the flue.

A backwardly and upwardly inclined bottom lining is provided beneath the boiler 1 composed of alternately arranged whole bricks on end and half bricks on side, the 60 bricks which are on end being arranged in staggered order. At the upper end of this inclined bottom lining there is an open work block 7 of latticelike construction composed of layers of brick on edge, the rows of bricks 65 of each layer being placed a slight distance apart and arranged at right angles to those of the next layer. As will be noted from Fig. 1, there is but a very small space left between the lower edge of the back end of 70 the boiler 1 and the top edge of the inclined bottom lining and the block 7.

At the front of the casing 2, beneath arch 5, there are several bell shaped burners 8 in the base 3 which communicate with a gas 75 main 9 connected up to a suitable gas generator. Each burner 8 is provided with a centrally located nipple 10 the upper end of which is slightly below the top thereof and the lower end of which communicates 80 with a pipe 11 within the main 9 connected to a head 12 mounted on the inner end of a compressed air supply pipe 13. This supply pipe runs longitudinally beneath the furnace, close to the surface of the bottom thereof, 85 and is connected to a fan, tank, or other suitable source of supply of compressed air.

The coal which would ordinarily be consumed in the furnace is, in this case, fed into the generator connected to the main 9. 90 The mixture of raw gases derived from the coal is led direct from the generator to the burners 8 and ignited in the usual manner through openings 6. The air supply is regulated by suitable valves in pipes 11, in the 95 usual manner. By this means sufficient oxygen is mixed with the crude gases to insure complete combustion of the same and the production of an intense heat.

The products of combustion flow from the 100 arch 5 backwardly along the inclined bottom and through the block 7, thence through the tubes of boiler 1 to the flue. The special arrangement of the brick lining provides throughout the length of the furnace a number of tortuous passages which retard the 105 flow of the products of combustion in such a manner that practically all of the heat

generated is utilized. During the operation of the furnace a draft is created through the openings 6. The inflowing air is retarded by the tortuous passages of the inner surfaces of the arch 5 and is thoroughly heated before entering beneath the boiler 1. In addition, the air which flows through pipe 13 is heated, after the furnace is started, from the heat retained by the bottom inclined lining of the furnace. This arrangement effectually prevents any sudden cooling of the boiler from the entry of cold air thus eliminating this danger and insuring a maximum of heating efficiency.

15 The tortuous passages formed by the projecting bricks in the inclined bottom form heat retaining means which causes the bricks to be quickly heated to incandescence. These incandescent bricks radiate an intense 20 heat and also act to ignite any gas flowing from the burners which is not consumed by the initial ignition at the furnace. This insures complete combustion of the gas as well as the radiation of intense heat, which 25 makes it practicable to increase the supply of gas so that the flames extend well under and about the boiler 1 thus making it possible to obtain a very quick generation of steam.

30 It is thought that the construction, operation, and use of the invention will be clear from the preceding detailed description.

Having thus fully described our invention, what we claim as new and desire to secure 35 by Letters Patent is:

1. In a furnace of the character described, a base provided with burners near its front end, a casing mounted on said base and provided with openings through its front wall, 40 a boiler mounted in said casing, an arch

erected at the front of the casing above the said burners and opening into the fire box beneath the boiler, an inclined bottom lining located beneath said boiler and provided with tortuous passages, an open work block 45 located at the back end of said inclined lining, means for supplying fuel to the said burners, and means for mixing air with the fuel supplied.

2. In a furnace of the character described; 50 a base; a casing mounted thereon and provided with openings through its front wall; a boiler mounted in said casing; an arch located at the front of the casing and communicating with the said openings and the interior of the casing, and having its interior surface provided with a plurality of tortuous passages; burners mounted in said base beneath the arch; a main communicating therewith and connected directly to a 55 gas generator; an air supply pipe mounted in said base and extending longitudinally of the same near the upper face thereof; pipes connected to the said supply pipe and extending into the said main; nipples connected thereto and extending up into the 60 said gas burners; an open work block at the back of the furnace; and an upwardly and backwardly inclined bottom lining extending from the back of the said arch to the 65 said block and provided with a plurality of tortuous passages.

In witness whereof we have hereunto set our hands in the presence of two witnesses.

PHILIPPE AUGUSTE ROCHON.
ANTOINE LAURENDEAU.
